OR D 11719 CA

No. 11,719

April 6, 1880

UNITED STATES PATENT OFFICE.

RUDOLPH SKOOG, OF NEW YORK, N. Y.

DESIGN FOR HOLDERS FOR BRUSHES.

SPECIFICATION forming part of Design No. 11,719, dated April 6, 1880.

Application filed March 1, 1880. Term of patent 7 years.

To all whom it may concern:

Be it known that I, RUDOLPH SKOOG, of the city, county, and State of New York, have invented a new and Improved Design for Holders for Brushes, Newspapers, &c., of which the following is a specification.

The figure is a photographic illustration of my design.

The leading feature of my design is the ornamental configuration of the holder.

There are four rods crossing each other near their ends, and secured to each other at the points of intersection by ornamental screws, nails, or buttons B. At a little distance from the upper and lower cross-rods of the frame A are placed other cross-rods, C, the ends of which meet the upright rods of the frame A.

The space between the inner cross-rods, C, is occupied by a lattice-work formed of smaller rods D, crossing each other diagonally and meeting the rods of the frame A at their points of intersection.

The space between the inner and outer cross-

rods, C A, is occupied by a lattice-work formed of two pairs of curved rods, E, crossing each other diagonally and secured at their bends to the said rods C A. The ends of the rods E meet the side rods, A, at their points of intersection with the cross-rods C A.

Above the top cross-bar, A, of the frame are placed ornamental scrolls F, formed of rods wound spirally and grouped with three larger spirals in the center and two smaller spirals at the ends.

Having thus described my invention, I claim as new and desire to secure by Design Patent—

The design for a holder for brushes, newspapers, &c., herein shown and described, consisting of the frame A, the inner cross-rods, C, the central lattice-work, D, the border lattice-work E, and the top scrolls, F.

RUDOLPH SKOOG.
